United States Patent Office

Des. 181,450
Patented Nov. 19, 1957

181,450

SPOON OR SIMILAR ARTICLE

José Barata y Barrera and Harry Morrison Martin, Jr.,
Baltimore, Md., assignors to The Steiff Company, Baltimore,
Md., a corporation of Maryland

Application January 7, 1957, Serial No. 44,416

Term of patent 14 years

(Cl. D54—12)

FIG. 1

Fig. 1 is a front elevational view of a spoon showing our new design;

Fig. 2 is a rear elevational view thereof; and

Fig. 3 is a side elevational view thereof.

We claim:

The ornamental design for a spoon or similar article, substantially as shown.
